Primary Examiner — Paula Greene(74) *Attorney, Agent, or Firm* — Jason H. Foster; Kremblas & Foster(57) **CLAIM**

The ornamental design for a visual coordination device, substantially as shown.

DESCRIPTION

FIG. 1 is a front perspective view of a visual coordination device showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.
